UNITED STATES PATENT OFFICE.

SIEGFRIED SHOLD, OF MANSFIELD, OHIO.

SAFETY DEVICE.

Application filed October 22, 1921. Serial No. 509,554.

To all whom it may concern:

Be it known that I, SIEGFRIED SHOLD, a subject of Sweden, residing at Mansfield, in the county of Richland and State of Ohio, have invented certain new and useful Improvements in Safety Devices, of which the following is a specification.

This invention relates to a safety device for use on machines provided with cooperating pressure elements such as punching presses and the like.

The primary object of the invention is to provide means of swinging a safety device between the cooperating pressure elements simultaneously with, or just after the commencement of a stroke of one element toward the other or the strokes of both toward each other, thereby providing means for shoving or pushing the hand (or any part of the anatomy of the operator) from the danger zone between the elements after the operator feeds the work between the pressure elements and prior to the time that the movable pressure elements or elements reach a relative position (or positions) with respect to each other that is, likely to result in injury to the operator.

Another object of the invention is to construct and operate a safety device that is adapted for automatically removing work from between the pressure elements, when part of the work is pressed to a higher or lower plane from the body portion of the work, the work being removed from between the elements by the return stroke of the safety device, thereby adding efficiency in the operation of the machine increasing the quantity of the output of the machine by saving time and labor that would be consumed by the operator in removing the work from between the pressure elements after being acted upon by the element.

A further object of the invention is to construct a safety device that is applicable to be used in cooperating with machines equipped with pressure elements which safety device is automatically operable for safety purposes when the machine is actuated intentionally by the operator, or when actuated without any act upon the part of the operator.

Further objects of invention consists in providing means for the vertical adjustment of the safety device, for changing the relative position of the safety device at the end of its travel in either direction with respect

to the pressure elements or dies and to vary or change the distance of the throw of the safety device to provide for swinging the safety device over or beyond, different sizes of pressure elements, dies or the like.

These and other objects are attained by the mechanism illustrated in the accompanying drawing in which:—

Fig. 1, is a side elevation of a part of the mechanism of a conventional type of punching press, showing the safety device applied to the press and in a position about to be swung or moved between the pressure elements.

Fig. 2, is a side elevation of a part of a punching press showing the invention applied thereto and in a position, preparatory to being swung or moved between the pressure elements upon its return stroke to its normal position,

Fig. 3, is a front elevation of a part of a punching press showing the invention applied thereto.

Fig. 4, is an enlarged plan view of the pivoted yoke supporting bracket taken on the line 1—1 of Fig. 1.

The type of press shown is a conventional type of punching press which is operated by a treadle mechanism, (not shown). The treadle mechanism is operated to impart a reciprocating movement to a rotatable shaft and one of the pressure elements of the press (or both) periodically or continuously through the medium of movable connecting mechanism which operate a clutch at the will of the operator. The treadle mechanism is not shown as it forms no part of the present invention.

The operation of the safety device is not dependent upon the treadle mechanism for its operation. The safety device will operate to perform its function by the eccentric shaft of the press when the shaft is rotated, by any power means.

In the drawings the invention is shown applied to a punching press as a conventional means of showing and describing its operation and functions. It will be apparent to those skilled in the art that the safety device can be applied without material alteration or change to machines of different types which are equipped with pressure elements and a rotating eccentric shaft without departing from the principle of the invention.

In the preferred application of the safety device to a punching press or the like as

heretofore set out, the frame of the press is represented by reference numeral 1. An eccentric shaft 2 is journaled in the usual manner in the frame and a flywheel 3 is 5 loosely journaled on said eccentric shaft and it cooperates with a clutch mechanism (not shown) to impart a rotating movement to the eccentric shaft 2 to periodically or continuously to actuate the movable element 10 or elements connected thereto to perform the work at the will of the operator by the actuation of an ordinary pedal mechanism of a press.

A reciprocating head or pressure element 15 4 is connected to the eccentric portion of the shaft 2 and is adapted to move or reciprocate the movable pressure element to and from the pressure element 5.

The parts hereinbefore described are common 20 in the construction of the type of punching press shown in the drawing and do not form any part of the present invention, except in their cooperative relation to the parts or elements which will now be described.

25 The shaft 2 as shown has its ends reduced at 6 to provide shoulder portions between the frame members to prevent endwise movement of the shaft. The reduced portion 6 of the conventional type of eccentric 30 shaft 2 is also provided with a key-way 7.

In the application of the invention to the type of press referred to a combined cam 8 and sector 9 is provided and mounted upon the reduced portion of the shaft 6 and held 35 rigidly in place by a key 10 which is fitted to the key-way 7 formed in the reduced portion 6 of the shaft and a corresponding key-way formed in the sector 9. It may be also held in place by the set screw 9.

40 A yoke shaped supporting bracket 11 is pivoted at a pre-determined point to the frame 1 of the press upon a bolt 12 which is threadably attached to the frame of the press. A shouldered spacer 13 is mounted 45 upon the bolt 12 between the arms of the bracket 11. A pin 14 is journaled adjacent to the ends 15 and 16 of the arm of the pivoted yoke bracket and is held in place and prevented from endwise movement by 50 cotter pins 17 and 18.

The ends 19 and 20 of a link bracket 21 are pivotally connected to the pin 14 and a roller 22 is journaled upon the pin between the free ends 15 and 16 of the arms of the 55 pivoted yoke shaped bracket 11. A bracket 23, is preferably secured to the press at a pre-determined vertical position with reference to the combined cam and sector by the bolts 24. The fixed bracket as shown is 60 preferably formed cone shape.

A plate 25 of suitable form and dimensions is pivotally hung upon a pin 26 which is in turn secured to the bracket 23. One end of the plate 25 is pivotally connected by a 65 pin 27 to the lower end of the link bracket

21. A safety device 28 comprising a swinging arm is also pivotally secured to the pin 26. An auxiliary L shaped member 29 is adjustably connected to the swinging arm 28 and the part 30 is bent to extend between the pressure elements and swing over and beyond the danger zone, between the pressure elements.

A slot 31 is formed in the pivoted plate 25 and a bolt 32 is provided to pass through the pivoted arm 28 and the slot 31 providing means to hold the part 29 in any adjusted position, so as to allow the parts 28-29 and 30 to swing with respect to the pressure elements, to different positions relative thereto.

A series of apertures 33 are provided in the pivoted plate 25 to permit the pin 27 which connects the link bracket 21 to the plate, to be connected to the plate at different points with respect to the fulcrum pin 26 of the plate, so as to provide means of varying or changing the distance of the throw of the part 30 of the safety device.

Referring to Fig. 1, reference numeral 34 represents a blank resting upon one of the pressure elements before the pressure elements have acted upon the blank or work. The part 30 of the safety device is adjusted so as to swing over the work or blank in close proximity thereto.

Reference numeral 35 represents a part of the blank pressed upward above the plane of the body portion of the blank or work permitting the part 30 to contact therewith on its return stroke and automatically eject, remove or "kick off" the pressed blank or work from between the pressure elements.

The operation of the invention in brief is as follows:—

The part of the safety arm 30 is vertically adjusted through the medium of slots 36 formed in the parts 28 and 29 and the bolt 37 is tightened to hold the part in the adjusted position, so that the part 30 will swing in close proximity to the work or blank. The throw of the part 30 is then adjusted so as to carry it beyond both ends of the pressure elements or dies as shown in Figs. 1 and 2. If it is desired to throw the part 30 in different relative positions with respect to the pressure elements or die, the arm 28 is adjusted as desired and held in its adjusted position by the bolt 32 so that its strokes move the part 30 either further away from or closer to the front or rear of the pressure elements or die.

In the event of the use of pressure elements or the dies of different sizes the throw of the arm carrying the part 30 is adjusted to correspond with the size of the die or pressure element by changing the pin 27 from one aperture 33 and moving into a different aperture of the series formed in the pivotal plate 25. This ad-

justment gives the required throw of the part 30 to correspond with the different sizes of dies and always maintain the part 30 in close proximity to the pressure element or dies irrespective of the size thereof.

An expansible spring 38 of any type is adapted to exert its pressure or tension to normally hold and retain the safety device and its connected mechanism in the positions shown in Fig. 1 and constantly forces the roller 22 in contact with the race of the cam 8. If the spring 38 should break, is removed, or out of repair the weight of the connecting parts of the safety device will swing the safety device carrying the part 30 by gravity to the position shown in Fig. 2 where it will remain until operated by the cam, to swing the part 30 between the pressure element preferably at the same time, as the movable pressure element starts on its down stroke.

The elements just described provide for the mathematical adjustment of the parts to carry out purposes and objects described herein. When all of the described adjustments have been made and the eccentric shaft 2 is rotated in the direction of the arrow either intentionally or without any act upon the part of the operator, and the cam is rotated from its normal position as shown in Fig. 1 the cam exerts a pressure against the roller 22 forcing the safety mechanism to swing or move part 30 forward between the pressure elements until the part 30 reaches the position shown in Fig. 2 at which times the roller 22 reaches the critical point 39 where it merges with the sector 9, and part of the cam 30 and its connecting mechanism is then maintained or retained in the position shown in Fig. 2 by contact of the roller 22 with the sector, until the sector is rotated to the point indicated at 40 at the point where the sector merges with the cam allowing the roller to travel on low part of the cam, gradually permitting the part 30 of the arm to be drawn or pulled back to its normal position (as shown in Fig. 1) by the spring 38, swinging or moving the part 30 between the pressure elements.

In adjusting the safety device to perform its functions it is preferably adjusted, so that the part 30 of the safety device will start to swing between the pressure elements at the same time as the movable pressure element or elements starts on its or their stroke toward each other, (or the other) or immediately thereafter and the return stroke of the part 30 is timed to commence to swing or move between the pressure elements at or about the time the movable pressure element or elements have traveled about one ($\frac{1}{2}$) half way or more upon its (or their) return stroke.

Attention is called to the fact that the

throw of the arm can also be varied more or less by changing the size of the combined sector and cam. The swinging speed of the arm carrying the part 30 will also be varied when the size of the combined sector 70 cam is changed.

Attention is further called to the fact that by changing the race of the sector, that the safety device can be maintained in idle position a pre-determined length of 75 time and by changing the race of the cam the safety device can be actuated to swing at pre-determined times.

I claim:

1. In a safety device for machines having co-operating pressure elements, a disk provided with a cam face mounted for rotation on the frame of the machine, a mechanism comprising a connected link mechanism provided with an arm which is adapted when 80 actuated by the cam to oscillate to and fro in the direction of the operator between the co-operating pressure elements, said oscillating arm being adapted to be adjusted to swing to different positions relative to 85 the die and punch and being adjustably secured to the pivoted plate to change the throw of the oscillating arm.

2. In a safety device for machines having co-operating pressure elements, a rotary 95 shaft journaled on the machine, a cam secured to the rotary shaft, a U shaped bracket pivotally mounted on the machine carrying a roller which roller is adapted to contact with said cam, a link pivoted to said bracket, 100 a second bracket secured to the frame beneath the aforementioned bracket and connected to said link, a pivoted member secured to said bracket, an adjustable arm secured to the pivoted member which is 105 adapted to oscillate between the pressure elements at pre-determined times when movement is imparted to the arm through the medium of the said cam.

3. In a safety device for punching 110 presses, a rotary shaft, a cam mounted thereon, a cam actuated means comprising a pivoted bracket, a pivoted plate and an adjustable link connected to the plate, which mechanism is secured to the frame of the 115 press and adapted to be actuated by the aforementioned cam to oscillate the arm of the cam actuated means at pre-determined times to and fro between the pressure elements and adjustably maintain said arm 120 at both ends of its throw free from, but adjacent to the pressure elements at the ends of its throw.

4. In a safety device for punching 125 presses, a rotary shaft, a cam mounted thereon for lateral adjustment, a pivoted cam actuated means carrying an arm which is secured to the frame of the press and adapted to be actuated by the aforementioned cam to oscillate said arm of the cam actuated 130

- means at pre-determined times, to position the arm beyond but adjacent to the pressure elements at both ends of its throw, the arm of said cam actuated means being adapted 5 to be adjusted to vary the throw and vertical position of the arm and adjusting it to assume different relative positions with respect to the pressure elements at each end of its to and fro movement.
- 10 5. In a safety device for machines having co-operating pressure elements, a disk provided with a cam face mounted for rotation on the frame of the machine, a mechanism comprising a pivoted bracket adapted 15 to contact with said cam, a link mechanism and a pivoted plate which is also provided with an arm which arm is adapted when actuated by said cam to oscillate to and fro between the pressure elements to a position free from the pressure elements at both ends of its throw but adjacent thereto.
- 15 6. In a safety device for machines having co-operating pressure elements, a rotary shaft, a cam mounted thereon, a pivoted 20 bracket mounted on the frame and provided with a roller which is adapted to contact with the cam, a second bracket fixedly mounted on the frame in spaced relation to the pivoted bracket, a plate pivoted to the 25 fixed bracket, a link connected to the pivoted bracket and plate, an arm adjustably secured to the pivoted plate, the arm and the link being connected to the pivoted plate in such a manner as to provide means of 30 varying the throw of the arm.
- 35 7. In a safety device for machines having co-operating pressure elements, a rotary shaft, a cam mounted thereon, a pivoted bracket carrying a roller mounted on the frame and adapted to contact with the cam, 40 a second bracket fixedly mounted in spaced relation to the pivoted bracket, a plate pivoted to the fixed bracket, a link connected to the pivoted bracket and plate, an arm adjustably secured to the pivoted plate, the 45 arm of the link being connected to the pivoted plate in such a manner as to provide means for changing the throw of the arm and its position at the end of its travel and means to adjust the end of the arm vertically.
8. In a safety device for a machine equipped with pressure elements, a rotary shaft journaled on the frame of the machine, a cam secured thereto, means pivoted 50 to the frame carrying a roller and so located thereon as to permit the roller to be yieldingly brought in contact with the cam, a plate pivoted to the frame in spaced relation to the pivoted bracket, a link connected 55 to the pivoted plate and bracket and an arm secured to the pivoted plate.
9. All of the elements defined in claim 8 characterized by the combination and construction of said parts so as to provide 60 means for adjusting the position of the arm relative to the pressure element at the end of its stroke carrying the stroke of the arm and for vertical adjustment of the end of the arm.

In testimony whereof I affix my signature.
SIEGFRIED SHOLD.
